UNITED STATES PATENT OFFICE

118,211

DESIGN FOR A DRESS

Morris Galowitz, New York, N. Y.

Application October 23, 1939, Serial No. 87,806

Term of patent 3½ years

To all whom it may concern:

Be it known that I, Morris Galowitz, a citizen of the United States and a resident of the city of New York, in the county of Kings and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress shown in Fig. 1. The characteristic feature of my design resides in the combination on the dress disclosed of the continuous, raised, stitched trim arranged on the front blouse and on the skirt pleats in the manner and position shown, and in association with the specific sleeve and pocket members as shown.

I claim:

The ornamental design for a dress, substantially as shown and described.

MORRIS GALOWITZ.
